INVENTOR.
George D. Wanner
ATTORNEY.

UNITED STATES PATENT OFFICE.

GEORGE D. WANNER, OF DAYTON, OHIO.

KITE REEL.

1,414,237.

Specification of Letters Patent. Patented Apr. 25, 1922.

Application filed April 18, 1921. Serial No. 462,105.

To all whom it may concern:

Be it known that I, GEORGE D. WANNER, a citizen of the United States, residing at Dayton, in the county of Montgomery and 5 State of Ohio, have invented certain new and useful Improvements in Kite Reels or the like, of which the following is a specification, reference being had therein to the accompanying drawings.

10 This invention relates to kite reels, having for its object to provide an improved reel of simple, substantial construction which can be made and sold at low cost.

An object of the invention is to produce a 15 kite reel having but few parts which are preferably assembled on the knockdown principle to enable handling of the same in specified lots in cartons of minimum capacity,—thus to effect both economy of space 20 and convenience and reduced cost of distribution.

In the accompanying drawings my improved reel is illustrated in a number of forms of modified construction,—the essential principle of the invention being applied in each construction in the drawings:

Fig. 1 is a view in elevation illustrating the improved reel in one form;

Fig. 2 is a view of the reel in a modified 30 form;

Fig. 3 is a view of the reel in a simpler form than that shown in Figs. 1 and 2, and

Fig. 4 is a view illustrating the knockdown construction of the reel.

35 Fig. 5 is a front elevation of the reel as shown in Fig. 1.

As above stated, the main object of the invention is to provide a kite reel which can be made and sold at low cost,—for 5¢ to 10¢, 40 thus bringing the cost easily within the means of boys interested in kites, and also to provide a reel which will be substantial, and satisfactory for its intended purpose.

To this end, my improved reel has few 45 parts and is of the simplest construction. As distinguished from the box-frame reels of the usual type which are more expensive, the reel of the present invention, as here shown, consists of a single support 1 for the 50 winding member,—the lower end of part 1 serving as a handle for holding the reel as it is being operated.

As illustrated in Figs. 1, 3, and 4, the winding member is mounted on the supporting member by means of a slip pin 2 which 55 serves as a stationary axis therefor. To pro-

vide for the knock down assembly of the parts, the cross blades 3 of the winding member are each slotted in one edge thereof as indicated at 4 and are adapted to be detachably assembled one blade with the other, with their inner and outer edges substantially flush, and having an aperture formed transversely therethrough, on the axial line of the assembled blades, to receive the slip 60 pin 2, the inner end of the pin having a sliding or pressure fit in support 1 which permits of its easy release therefrom.

As shown in Figs. 1, 2, and 3, a laterally projecting finger piece 5 is secured in the 70 outer edge of one of the blades 3 to serve as a means for operating the reel.

In Fig. 2 a modified construction is illustrated of the means for mounting the reel member on the supporting member and for 75 operating the reel. In this construction a crank shaft 6 is rotatably supported in part 1,—the reel blades 3 being constructed and assembled as above described but secured in operatively fixed relation to shaft 6,—thus 80 to be operated by turning of the shaft.

In the form illustrated in Fig. 1 an operable guide 7 is provided for the kite string as it is wound on the reel; this feature consisting of a length of spring wire, as here shown, having its lower end 8 anchored in support 1, and its upper end 9 bent inwardly substantially at right angles to the body length of the wire, and passing through a slot 10 formed in the upper end of part 1, 90 thus serving as a guide for the reciprocal movement of the wire,—the bent end of the wire being formed into a loop 11 to receive the kite string. The wire as assembled on the supporting member normally springs 95 outwardly as illustrated in Fig. 1, and is adapted to be moved inwardly by a slight pressure of the thumb as the device is held in one hand of the operator as the reel is being turned with the other,—thus with alternate pressure and release of the spring the same will be actuated reciprocally to effect even winding of the string on the reel.

In Figs. 2, 3, and 4 a fixed guide 12 for the kite string is shown which serves to direct the string to the reel as the same is being wound but does not regulate the cross-wise winding.

In Fig. 3 a form of the reel is shown in which a single blade 3 is used, the construction otherwise being the same as that illustrated in Fig. 4. The simpler construction,

enables the reducing of cost and sales price to the minimum, and provides a reel which meets the requirements though not as well as the more complete forms shown.

5 The knock down construction of the reel, in the several forms here shown, is illustrated in Fig. 4 in which one of the blades 3 is detached, thus permitting the parts to lie flat in a carton or any suitable container 10 for handling and shipping the reels in quantities.

Having described my invention, I claim:

15 1. In a kite reel, the combination with a supporting member comprising a handle, of a winding member axially supported on said member, a reciprocally operable guide for a kite string secured to the supporting member adjacent said handle, and actuating means for the winding member.

20 2. In a kite reel, the combination with a supporting member comprising a handle, of a winding member axially supported on said member, a spring actuated, reciprocally operable guide for a kite string secured to the

supporting member adjacent said handle, 25 and actuating means for the winding member.

3. In a kite reel, the combination with a supporting member comprising a handle and having a slotted end, of a winding member 30 axially supported on said member, a reciprocally operable guide for a kite string secured to the supporting member adjacent said handle and operable through said slotted end, and actuating means for the winding member.

4. In a kite reel, the combination with a single supporting member, of a pin secured in said member and extending laterally at right angles thereof, a winding member axially supported on said pin, a guide for a kite string secured to and extending laterally of the supporting member over said winding member, and an actuating finger piece secured to and extending laterally of the winding member.

In testimony whereof I affix my signature.
GEORGE D. WANNER.
